LAP WINDER

Robert S. Curley, Biddeford, Maine, assignor to
Saco-Lowell Shops, Boston, Mass., a corpora-
tion of Maine

Application April 13, 1950, Serial No. 155,590

4 Claims. (Cl. 242—55.1)

1

This invention relates to improvements in that class of machines used in the textile industry to take a lightly compressed lap made up of a sheet of textile fibers or a number of slivers, compress it, and wind it up in a compressed cylindrical package.

Such machines have an important function in the making of a good lap, as the manner in which the lap is compressed and wound up in readiness for use in subsequent operations has a great effect on the uniformity of the ultimate product, e. g. evenness of a sliver resulting from subsequent operations for which the lap provides the starting material. The pressure used to compress the lap as it is wound up should be substantially constant along the length of the wound material in order to give an even lap of constant density, one in which the textile fibers are distributed evenly along the length of the lap, and in which all the fibers are compressed an equal amount. If the pressure employed is too little, the textile fibers on the surface of the lap will have a tendency to cling to those on the adjacent layer in the lap package, thus transferring fibers from one layer to another, i. e. delaminate and cause variations in the distribution of fibers along the length of the lap. If the pressure is too great, the fibers will become so matted that a small amount of felting takes place, increasing the work of machinery employed in subsequent operations and frequently causing the detachment of fibers in bunches in such machinery, causing neps which destroy the uniformity of the sliver.

Furthermore, a lap must have a uniform thickness at least widthwise of the lap, as otherwise the lap will wind up into a compressed package of conical shape, which cannot readily be used in subsequent operations since one side of such a conical lap will be somewhat thicker than the other.

In the machines long used to compress and wind up a lap, the pressure on the lap has been maintained by the friction of a brake band pressed by a lever against the surface of a pulley which in turn is rotated, through suitable gearing, by the lap racks as they rise vertically with the lap arbor due to the increasing size of the lap package as the lap is wound up by a pair of underlying driven rollers. Under these conditions, the required pressure on the lap cannot be firmly applied until a sufficient length of the lap is wrapped around the lap arbor to start the lap racks rising. Consequently, at the start of the winding operation, the friction pulley is held in

2

a stationary position, and during such time that the lap package is building up to produce sufficient force to start the pulley revolving, the coefficient of friction is that of static friction. As soon as the lap package has built up sufficiently to start the pulley revolving, the coefficient of friction becomes that of kinetic friction, which is very much smaller than the coefficient of static friction, and the pressure on the lap being wound up abruptly decreases. Thus, when the pulley starts to rotate, the amount of force necessary to transfer from static friction to kinetic friction is so great that the pulley goes by and stops its forward motion, and the pressure on the lap being wound up decreases. Because of this, the racks have a tendency to rise at an uneven rate, particularly during the initial stages of compressing and winding a lap, thus causing the pressure on the lap to vary and, in turn, form alternate hard and soft places along the length of the lap. For instance, in the operation of such a prior machine, the first few lineal yards of a lap are commonly 7% to 10% heavier than the remainder of the lap and cannot well be used in subsequent operations if a uniform sliver is required. Consequently, a certain amount of the lap initially wound is usually returned to the opener, frequently as much as 2% to 4%.

By the present invention, a simple and practical mechanism is provided which supplies a substantially constant pressure to the lap at the outset, as soon as it has begun to wind up on the lap arbor, reducing the lengthwise variations in the first few yards as well as those of the entire lap and producing a far more even and better lap. The invention, for the first time in the art, provides in a compressed cylindrical package a lap that is of uniform thickness, both widthwise and lengthwise thereof.

A feature of my invention is that by its use the entire lap may be used in subsequent operations, since the variations in weight in the first few yards of a lap produced by the mechanism of my invention are no greater than the variations in weight in the remainder of the lap. Thus it is unnecessary to remove a length of the lap and return it to the opener for reworking.

A further feature of my invention is the quick release of pressure provided which prevents damage to the outer layer of the lap package when it is being removed from the lap winding machine.

Still further features of my invention are its simplicity and ease of installation on existing lap winding machines.

For the purpose of further explaining my invention, reference is made to the following drawings, in which:

Fig. 1 is an elevational view of the delivery end of a lap winding machine embodying my invention;

Fig. 2 is a side view, partly broken away, of a portion of the machine of Fig. 1; and

Fig. 3 is a cross-sectional side view of the machine of Fig. 1 taken on the line 3—3 of Fig. 1.

Referring to the drawings, the lap winding machine embodying my invention includes a frame 10 on which are rotatably mounted a pair of rollers 12 and 14 in closely adjacent parallel positions. The rollers 12 and 14 are provided with gears 13 and 15 respectively by which they are positively driven by any suitable driving means (not shown) through a pulley 20 mounted on shaft 70 driving gears 13 and 15 through gears 22, 24 and 26.

A lap 16 of textile fibers supplied by conventional opening and picking machines, not shown, or made up of a number of slivers passes over the rear roller 14 and is compressed and wound up into a compressed cylindrical package 17 on a lap arbor 18 overlying said rollers 12 and 14, and frictionally rotated thereby. The lap arbor 18 is rotatably mounted in semi-circular bearings 28 for movement in a vertical plane substantially perpendicular to the plane of the axes of rollers 12 and 14 and midway between said axes. Each lap arbor bearing 28 is mounted for vertical movement on a rack 30 which rides in a substantially vertical track 32 on frame 10. In order to maintain the arbor bearings 28 at equal distances from the axes of rollers 12 and 14 as the lap arbor 18 rises due to the increasing size of the lap package 17, a positive mechanical connection is provided between the arbor bearings 28, comprising pinions 34 mounted on a common shaft 36 engaging racks 30. Thus any vertical movement of one bearing 28 will be transmitted to the other bearing 28, ensuring equal movement of said bearings and at all times maintaining the axis of arbor 18 parallel with the axes of rollers 12 and 14 so that the lap 16 will be compressed to a constant thickness widthwise of said lap and ensure the formation of the necessary cylindrical package 17 rather than a somewhat conical one which is undesirable in subsequent operations.

In accordance with my invention, the pressure between the lap arbor 18 and the rollers 12 and 14 is provided by a reversible fluid motor, preferably a compressed air motor, generally designated at 40, mounted at the bottom of frame 10, the shaft 64 of said motor including a rack 66 engaging a pinion 68 on shaft 36. The fluid motor 40 has a casing 42 and a piston 44 forming rear chamber 46 and forward chamber 48. Lines 50 and 52 are provided to connect said chambers to a four-way valve 54 which is supplied with fluid at suitable pressure by line 62, a reducing valve 60 and a line 58 between said reducing valve and said four-way valve. The four-way valve is normally arranged to connect line 52 and the forward chamber 48 of fluid pressure motor 40 to the fluid under pressure in line 58, as hereinafter more fully explained.

The four-way valve 54 is arranged to be automatically operated by a knock-off mechanism to raise the lap arbor bearings 28 when the lap package 17 has reached a desired size so that the lap package may be removed from the machine. Such knock-off mechanism is further

arranged to disconnect from a source of power the usual calender rolls (not shown) provided in such a machine to compress the lap 16 prior to its being compressed and wound up by rollers 12 and 14 on lap arbor 18 in order to stop the calender rolls to break the lap 16 and wind the broken end on lap package 17. Referring to Figs. 1 and 3, the shaft 70, on which pulley 20 is mounted, is pivotally mounted on the frame 10 in a self-aligning bearing 71. The opposite end of said shaft 70 is rotatably mounted on a lever 72, said lever 72 being pivoted on a stud 73 on frame 10. A gear 74 mounted on shaft 70 adjacent said lever 72 is provided to engage a gear 76 for driving the usual calender rolls (not shown), said gear 76 being rotatably mounted in bearing 77 on frame 10. The gear 78 concentric with and driven by gear 76 drives a gear 80, said gear 80 being mounted for swinging movement by means of a link 82 pivotally mounted by stud 83 on frame 10. Gears 78 and 80 are provided with co-acting hunting-teeth 84 and 86 so that when hunting-tooth 84 on gear 78 contacts tooth 86 on gear 80, said gear 80 will be swung away from gear 78 to move arm 88 rigidly mounted on and extending downwardly from link 82. Said arm 88 is normally retained in engagement with a latch 90 on lever 72 so that when said arm 88 is moved by the action of hunting-teeth 84 and 86, said lever 72 will be released and will drop downwardly, thus disconnecting gears 74 and 76 to disengage the calender rolls from the source of power.

Lever 72 is further provided with a link 92 to operate the four-way valve 54 through a foot lever 94 pivoted on frame 10 and a Z-bar 96 arranged to operate treadle 56 of four-way valve 54 to connect rear chamber 46 of motor 40 to fluid under pressure in line 58 to positively elevate

racks 30 and bearings 28.

In operation, if it is desired to wind up the lap 16 into a compressed cylindrical package 17 on arbor 18, assuming the lever 72 is in its lowered position, the Z-bar 96 depresses the treadle 56 causing the valve 54 to connect rear chamber 46 of air-motor 40 to a source of fluid pressure in line 58 to move the racks 30 and bearings 28 to the upper limit of their travel. To start a new lap package 17, the foot lever 94 is pressed down to raise the lever 72 and engage gear 74 with gear 18, thus starting the calender rolls. At the same time arm 88 will engage latch 90 and be retained thereunder. The lap 16 is then placed over rollers 12 and 14, the arbor 18 placed over the lap 16, and the lap 16 transferred around the arbor 18 and tucked into the nip between arbor 18 and roller 14 in the usual manner. The foot treadle 56 is then operated to connect forward chamber 48 of motor 40 to a source of fluid pressure in line 58 causing rack 66 on fluid motor shaft 64 to rotate pinion 68 on shaft 36 and move lap racks 30 and bearings 28 downward to engage arbor 18. After bearings 28 engage arbor 18, the pressure in forward chamber 48 of fluid motor 40 will build up and urge the arbor 18 toward the rollers 12 and 14 to compress the lap 16 and begin to wind it into a compressed cylindrical package 17.

As the lap 16 builds up into the cylindrical package 17, arbor 18 will move bearings 28 and their associated racks 30 upward, but such movement will be resisted by the constant pressure of the fluid under pressure in forward chamber 48 of air-motor 40, thus urging the arbor 18 toward the rollers 12 and 14 to compress the lap

16, and applying a constant pressure at all times to the lap 16 as it is wound up into a cylindrical package 17.

After the lap package 17 has reached the desired size, as determined by the relation of gears 78 and 80, hunting-tooth 84 on gear 78 will engage hunting-tooth 86 on gear 80, moving gear 80 and its associated arm 88 to disengage said arm from latch 90 and allow lever 72 to drop downwardly to disengage calender driving gear 76 from gear 74. At the same time lever 72 will operate four-way valve 54 through link 92, foot lever 94 and Z-bar 96 to connect rear chamber 68 of motor 40 to a source of fluid pressure in line 58. Motor 40 will then move rack 63 to rotate pinion 68 and move racks 30 and bearings 28 upward to release the ends of arbor 18. The lap package 17 wound on arbor 18 may then be removed from the machine.

Various changes and modifications of my preferred apparatus herein shown and described may be made without departing from the spirit of my invention, for instance, a fluid motor could be arranged to act directly on either the lap arbor bearings or the lap racks. These and such other changes are contemplated as may come within the scope of the appended claims.

I claim:

1. In a machine for winding on a rotatable arbor a lap of textile fibers into a compressed roll, a frame, a pair of adjacent parallel rollers mounted on said frame for frictionally rotating a lap on the arbor, arbor retaining bearings on each side of said frame mounted for vertical movement, racks affixed to said bearings respectively and movable vertically therewith, a rack driving shaft rotatably mounted on said frame, pinions fixed to said shaft for rotation therewith engaging said racks, and an air motor connected to rotate said pinions through said shaft to move said racks and said bearings downwardly and to resist rotation of said shaft to thus resist rotation of said pinions and upward movement of said racks, bearings and the arbor to compress the lap.

2. In a machine for winding on a rotatable arbor a lap of textile fibers into a compressed roll, a frame, a pair of adjacent parallel rollers mounted on said frame for frictionally rotating a lap on the arbor, arbor retaining bearings on each side of said frame mounted for vertical movement, racks affixed to said bearings respec-

tively and movable vertically therewith, a rack driving shaft rotatably mounted on said frame, pinions fixed to said shaft for rotation therewith engaging said racks, an air motor having a piston, a rack on said piston, and a piston rack engaging pinion mounted in rotatively fixed position on said shaft whereby said motor rotates said shaft and pinions fixed thereto to move said first-mentioned racks and said bearings downwardly and resists rotation of said shaft to thus resist rotation of said pinions fixed thereto and upward movement of said first-mentioned racks, bearings and the arbor to compress the lap.

3. In a machine for winding on a rotatable arbor a lap of textile fibers into a compressed roll, a frame, a pair of adjacent parallel rollers mounted on said frame for frictionally rotating a lap on the arbor, arbor retaining bearings on each side of said frame mounted for vertical movement, racks affixed to said bearings respectively and movable vertically therewith, a rack driving shaft rotatably mounted on said frame, pinions fixed to said shaft for rotation therewith engaging said racks, a reversible air motor with a piston having a rack, and a piston rack engaging pinion mounted in rotatively fixed position on said shaft whereby said motor in one direction rotates said shaft and pinions fixed thereto to move said first-mentioned racks and said bearings downwardly and resists rotation of said shaft to thus resist rotation of said pinions fixed thereto and upward movement of said first-mentioned racks, bearings and the arbor to compress the lap and in the other direction moves said first-mentioned racks and said bearings upward to relieve the pressure on said lap and elevate said bearings.

4. A machine as claimed in claim 3 having a knock-off mechanism arranged and connected to actuate said air motor positively to elevate said first-mentioned racks and bearings.
